UNITED STATES PATENT OFFICE.

GEORGE M. KEEFAUVER, OF FIATT, ILLINOIS.

COMBINED LEVEL AND GAGE.

1,074,367.

Specification of Letters Patent. Patented Sept. 30, 1913.

Application filed February 4, 1913. Serial No. 746,194.

To all whom it may concern:

Be it known that I, GEORGE M. KEEFAUVER, residing at Fiatt, in the county of Fulton and State of Illinois, have invented an Improved Combined Level and Gage, of which the following is a specification.

This invention is in the nature of an improved tool or appliance that is more especially designed for use when building forms for concrete walks, driveways, feed floors, etc., and also for placing "nailers" in building headers over doors and windows.

Primarily, my invention has for its object to provide a tool or appliance of the character stated of a simple and economical construction, that can be conveniently handled and adjusted for use and which effectively serves its intended purposes.

With other objects in view that will hereinafter appear, my invention consists in the peculiar construction and novel arrangement of the parts hereinafter explained, specifically pointed out in the appended claims and illustrated in the accompanying drawings, in which:

Figure 1 is a perspective view of my invention, the same being shown in use in building a concrete walk. Fig. 2 is a longitudinal section of my improved tool or appliance. Fig. 3 is a cross section of the same on the line 3-3 on Fig. 2. Fig. 4 is a perspective view of one of the extensible or gage members. Fig. 5 is a detail view of a modified arrangement for joining the clamping means with the extensible or gage members. Fig. 6 is a cross section thereof.

In the practical application of my invention, I use a leveling tool that comprises the conventional form of body or stock 1, having a leveling bulb 2 in the upper face and the vertically disposed bulbs 3 in the opposite ends thereof, a carrying handle 4 being disposed in the top edge of the body that straddles the transverse sight grooves 5, for the leveling bulb 2, as shown. The under or lower edge of the body 1 has a longitudinal groove 6 and in which play the vertical ribs 7 of the extensible or gage members 8, one for each end of the level.

The members 8 are T-shaped in cross section and their lateral portions or flanges 9 form bearing portions for riding over the lower edge of the body 1, at opposite sides of its longitudinal groove 6. At the outer end, each member 8 has a transversely widened bearing portion 10, which portions when

the members 8 are of metal, are preferably integral with the said members and when the members 8 are of wood are nailed to the said members 8. Each gage member 8 also has a pendent lug 11 that serves to locate the width points for placing the side boards or forms for the walk, see Fig. 1.

12-12 designate hangers, one for each gage or extensible member 8, and they fit loosely on the said members. The hangers 12 fit into sockets 13 in the under edge of the level body 1, as is clearly shown in Fig. 3, by reference to which it will be also noticed the socket 13 merges with the lower end of a vertical opening 14 that extends through the upper edge of the level body, it being provided to receive the clamping rod 15 that pivotally connects with the stirrup 12, and has its upper end threaded to receive the winged clamping nut 16.

An indicator 17 is attached to each member 8 to travel over an indicator or scale plate 18 secured on the face of the level body, the figures of which, are stepped off from the center in both directions, and indicate the different walk widths, it being understood that when the two members 8 are set to the position shown in Fig. 1, the distance across from one lug 11, to the other lug 11 is two feet six inches.

From the foregoing description, taken in connection with the drawing, it is believed the operation and the advantages of my invention will be readily understood.

Instead of using the stirrup connection, as shown in Fig. 3, the clamping rod may be connected to the gage member 8, as shown in Fig. 6. In this form, the vertical portion of the body of the said member has short lateral flanges 19, that slide through the hangers or yokes 20, pivotally suspended from the rod 15. When this latter form is used, the level body has guide grooves 21 to receive flanges 19.

While my invention has been shown and described as especially adapted for use in laying off concrete walks, I desire it understood that the same may also be used for placing "nailers" in headers over doors or windows.

What I claim is:-

1. A combined level and gage comprising a body or stock having a bubble glass, a gage member longitudinally extensible from the stock or body, said member having a gage lug, means operable from the upper

edge of the stock for clamping the extensible member in its adjusted positions, the said means comprising a screw rod that extends up above the upper edge of the stock, a nut that engages the rod and the said stock, and hangers pivotally suspended from the rod within which the said extensible member is held in slidable engagement, said stock having chambered portions to receive said hangers.

2. An implement of the character stated comprising a spirit level, having its body or stock provided with a longitudinal groove in its lower edge that extends through the opposite ends of the said stock, a pair of oppositely extensible members slidably mounted in the said groove, each of the members having a gage lug at the outer end, means operable from the upper edge of the level body for clamping the extensible members in their adjusted position, a scale plate on the said level body common to both of the extensible members and an indicator connected to each of the said members and movable over the scale plate.

3. A combined spirit level and gage, comprising the following elements in combination; a stock or body having the usual bubble glasses, a longitudinal groove in its lower edge that extends the full length thereof, a socket at each end that bisects the said groove and terminates in vertical aper-

tures that open through the top of the level body, an extensible member for each end of the said body slidably mounted in the said groove, each of the said members having a gaging lug, clamping means for said members comprising a hanger held in each socket of the body that takes around their respective extensible member, a screw rod mounted in each of the vertical apertures in the stock, said rods being pivotally connected with their respective hangers and a nut engaging each screw rod and the top edge of the level body.

4. A combined level and gage, comprising a body or stock having a groove in its underside, a gage member including a web longitudinally slidable in said groove, and a base flange adapted to contact with the bottom face of said stock, said gage member being longitudinally extensible from the stock, a hanger shaped to embrace and slidably hold said gage member, said stock having a chamber to receive said hanger, a bolt pivoted to said hanger and projecting through said stock, and a nut co-operative with said bolt to draw said hanger toward said stock and thereby hold said gage member in its adjusted positions.

GEORGE M. KEEFAUVER.
